US00D602772S

(12) **United States Design Patent**
Suzuki et al.

(10) **Patent No.:** **US D602,772 S**
(45) **Date of Patent:** **** Oct. 27, 2009**

(54) **PACKAGE**

(75) Inventors: **Takeo Suzuki**, Tokyo (JP); **Michiko Sakamoto**, Tokyo (JP)

(73) Assignee: **Pentax Corporation** (JP)

(**) Term: **14 Years**

(21) Appl. No.: **29/329,521**

(22) Filed: **Dec. 16, 2008**

D67,875 S * 7/1925 Cluett D9/432

Primary Examiner—Susan Bennett Hattan

(74) *Attorney, Agent, or Firm*—Sughrue Mion, PLLC

(57) **CLAIM**

The ornamental design for a package, as shown and described.

DESCRIPTION

FIG. 1 is a perspective view of the front, left and bottom of a package according to a first embodiment showing our new design;

FIG. 2 is a top plan view thereof;

FIG. 3 is a front view thereof;

FIG. 4 is a rear view thereof;

FIG. 5 is a left side view thereof;

FIG. 6 is a perspective view of the front, left and bottom of a package according to a second embodiment showing our new design;

FIG. 7 is a top plan view thereof;

FIG. 8 is a front view thereof;

FIG. 9 is a rear view thereof;

FIG. 10 is a left side view thereof;

FIG. 11 is a perspective view of the front, left and bottom of a package according to a third embodiment showing our new design;

FIG. 12 is a top plan view thereof;

FIG. 13 is a front view thereof;

FIG. 14 is a rear view thereof; and,

FIG. 15 is a left side view thereof.

The elements shown in the drawing figures using broken lines depict environmental structure only, and form no part of the claimed design.
